THERMAL SWITCH

Richard H. Schmitt, Schenectady, N. Y., assignor
to General Electric Company, a corporation of
New York

Application June 29, 1934, Serial No. 733,005

9 Claims. (Cl. 200—116)

My invention relates to thermal switches, more particularly to switches arranged to control the starting of motors, and has for an object the provision of a simple, inexpensive and reliable switch of this character.

In carrying out my invention in one form thereof, I provide a releasable connection between an operating handle and the contact carrying member, which connection is arranged to be released 10 in response to the operation of a thermal device connected in the motor circuit. The releasing mechanism is arranged so that as the switch is operated to its open circuit position the releasing mechanism is automatically reset in position to 15 be held by the thermal device and the switch operating handle is operated from the "on" to the "off" position.

For a more complete understanding of my invention, reference should now be had to the accompanying drawing wherein I have shown in Fig. 1 a plan view of switch embodying my invention; Fig. 2 is a sectional elevation taken on the line 2—2 of Fig. 1; Fig. 3 is a perspective view of the switch, while Fig. 4 is a plan view showing the 25 relation of the thermal overload devices with a portion of the tripping mechanism located on the lower or left-hand side of the insulating base.

Referring to the drawing, I have shown my invention in one form as applied to a three-pole switch 10 provided with a base 11 formed of insulating material. The base is secured within a metal switch box 12 by means of brackets 13 and 14 which cooperate with ledges 15 and 16 formed integrally with the base member 11, and 35 by screws 18 and 19, which screws extend through the insulating base member and into screw-threaded engagement with the switch box 12.

A switch member 22, formed of insulating material and pivotally mounted on a pivot pin 23 extending through the respective sides of a U-shaped metallic frame 24, supports the movable bridging contacts 25, 26 and 27. The frame 24 is mounted on the right hand side or upper side of the base 11 as viewed in Fig. 2. The member 45 22 and the movable contacts are normally biased to an open circuit position by means of a spring 28 wound about the pivot pin 23, one end of the spring bearing against the cross member of the frame and its other end bearing against a pin 30 carried by the switch member. The switch member 22 is operatively connected to an operating handle 31 by means of a toggle link 32 connected by the pin 30 to the switch member and a toggle link 33 connected at one end by a pivot pin 34 50 to the handle 31, the two links being connected

together by a knee pivot pin 37. The collapsible driving connection or toggle formed by the links 32 and 33 is normally maintained in a straightened and slightly overset position, as shown in the drawing, by a coil spring 38 wound 5 about the knee pivot pin 37. A cross portion 33a of the link 33 forms a stop for the toggle in the overset position, i. e. the position when the knee pivot pin 37 is located slightly below a line taken through the centers of the pins 30 and 34 of Fig. 10 2. Consequently, the force of the spring 28 does not tend to collapse the toggle.

When the handle 31 is in the fully closed position, shown in Fig. 2, the bias of the spring 28 is applied directly by the toggle to the handle in 15 a direction to hold the handle in its "on" or fully closed position. Thus the bias of the spring 28 is applied to the handle in the direction of a line extending from the center of the pin 30 through the center of pin 34. This line of the applied 20 force passes below the pivot pin 31a of the handle and thereby tends to rotate the handle in a counter-clockwise direction as viewed in Fig. 2. The "on" position of the switch, however, is determined by the engagement of the projection 25 39 on the handle with a pin 40 extending between opposite sides of the frame 24. The compression 30 springs 41, 42 and 43 associated with the respective movable bridging contacts 25, 26 and 27 and resiliently securing the contacts on the switch 35 member 22 are compressed as the movable contacts are operated into engagement with their associated pairs of stationary contacts only one pair of which, the contacts 46 and 47, being shown. Besides insuring a strong contact pressure and 40 permitting automatic adjustment for irregularities in the contact surfaces, the compression springs 41—43, inclusive, assist in accelerating the switch member 22 during its operation to its open circuit position. By rotating the switch 45 handle 31 in a clockwise direction, as viewed in Fig. 2, the pivot pin 34 is rotated to the opposite side of the pivot pin 31a so that the springs 28, 41, 42 and 43, quickly open the switch.

The three-pole switch 10 is particularly applicable to the control of a three-phase motor and in order to insure the automatic operation of the switch to its open circuit position in the event of an overload on any one of the phases, two thermal overload devices 50 and 51 are connected in 50 the two outside poles of the switch, i. e. in series circuit relation, respectively, with the two outside contacts 25 and 27. As shown, the overload device 50, of the solder-film type, is provided with a heating coil 53 mounted adjacent to and in 55

spaced relation with a stationary bushing 54, both the coil and bushing being mounted on the right hand or upper side of the base. A shaft 55, normally rigidly secured to the bushing 54 by means of a solder film, extends through the base and rigidly supports at one end a releasing gear 56, shown in Fig. 4. The thermal overload device 51 provided with a releasing gear 57 is of identical construction with the device 50.

10 The tripping or release mechanism operated in response to the release of either one, or both, of the gears 56 and 57 consists of a bifurcated tripping lever 60 pivoted on the pin 40. One arm 61 of this lever, located on the upper side, as viewed in the drawing, of a resetting extension 62 formed integrally with the switch member 22, is arranged for movement into engagement with the knee portion of the toggle. The other arm 63 located on the opposite or lower side of the resetting extension 62 extends through an aperture 11a provided in the base and through a slot 64 provided in a floating latch member 65 to which are secured two latching pawls 66 and 67. The pawl 66 is pivoted at 70 to one end of the latch member, 25 the opposite end 71 of the pawl engaging the gear 56. Similarly, the pawl 67 is pivoted at 72 to the latch member 65 while its opposite end 73 engages the gear 57. A tension spring 75 connected between a stationary supporting plate 76 and the 30 end 63a of the arm 63 of the tripping lever serves to bias the tripping member 60 for movement of its other arm 61 to break the toggle. The pawls 66 and 67 are biased towards the respective releasing gears 56 and 57 by a leaf spring 80 carried 35 by the plate 76. This plate 76, secured to the bottom of the base 11 by a screw 81; (Fig. 2) has an extension 76a which acts as a guide for the latch member 65 located between the extension and the base.

40 A very compact switch mechanism is obtained by mounting the operating mechanism and the tripping mechanism on opposite sides of the base 11. Furthermore, since the overload tripping mechanism is concealed in its position below the base, there is less likelihood that the operation of the switch will be impaired due to tampering by the unskilled.

Continuing with the description of my invention, it will be assumed that a predetermined 50 overload current flows through the heating coil 53 to cause the release of the gear 56 for rotation. The tension spring 75 thereupon rotates the latch member 65 and the arm 66 in a counter-clockwise direction about the pivot pin 72, as viewed in Fig. 4, the arm 67 being held stationary by its associated gear 57. The arm 63 of the tripping lever 60 extending through the slotted latch member 65 and rotating with it, moves the other arm 61 against the knee of the toggle and thereby moves 60 the knee pivot pin 37 upward, as viewed in the drawing, to break or collapse the toggle. A very small movement is required since the toggle is but slightly overset, the opening of the switch occurring very quickly due to the combined action of the springs 28 and 41—43, inclusive.

65 As the opening movement of the switch member 22 begins, its resetting extension 62 engages the arm 63 to return the tripping member 60 to its original position, against the force applied by the 70 spring 75, the switch opening springs being many times stronger than the spring 75. The return movement of the arm 63 rotates the latch member 65 and the pawl 66 about the pivot pin 72 to their original positions completing the automatic return 75 setting of the tripping mechanism.

It will be observed that coil spring 38 encircling the knee pivot pin 37 biases the toggle links 32 and 33 to their straightened positions. This spring 38 functions to straighten the toggle, after the switch has tripped open, and in so doing rotates the handle 31 from its "on" position to its "off" position. Consequently to reclose the switch it is only necessary to move the handle 31 to its "on" position.

If an attempt is made to close the switch before 10 the solder film has cooled sufficiently to maintain the gear 56 stationary, however, the movement of tripping lever 60 will collapse the toggle and thereby prevent the closing of the switch.

Since the toggle or collapsible driving connection is located between the handle 31 and the switch member 22 the switch is trip free; that is, the overload opening of the switch occurs irrespective of the position of the handle 31. Similarly, the automatic resetting of the thermal 20 tripping mechanism is independent of the position of the handle 31.

In case of an overload which frees the gear 57, it will be understood that the latching member 65 and the pawl 67 rotate about the pivot pin 70 to 25 operate the tripping member 60 to trip the switch. In case of an overload which frees both gears 56 and 57, the latching member 65, pawls 66 and 67 and the tripping member 60 move longitudinally to trip the switch to the open circuit position. 30 In each case the rigid engagement of the resetting extension 62 with the arm 63 of the tripping member 60 resets the thermal tripping mechanism.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

40 What I claim as new and desire to secure by Letters Patent of the United States, is:—

1. A switch comprising a base formed of insulating material provided with an aperture, a switch member, means mounting said switch member for movement between open and closed circuit positions, an opening spring for biasing said switch member to said open circuit position, an operating handle, pivot means mounting said handle for rotation between on and off positions, a collapsible toggle pivotally connecting said handle and said switch member and normally forming an operating connection therebetween, said handle when rotated from its off to its on position operating said switch member to said closed circuit position against the bias of said opening spring, a trip member biased for movement from one position to a second position to collapse said toggle, said trip member extending through said aperture, a thermal responsive device on the opposite side of said base from said switch member restraining said trip member against movement from said one position but operable on overload to free said trip member to operate said switch member to said open circuit position, and means operable with said switch member as said switch member moves to its open circuit position to return said trip member to said one position.

2. A switch comprising a switch member, pivot means pivotally mounting said switch member for movement between open and closed circuit positions, said switch member being provided with an extension adjacent said pivot means, a spring normally biasing said switch member to said open circuit position, an operating handle 75

for said switch, toggle means between said handle and said switch member normally forming an operating connection between them and operable to hold said switch member in said closed circuit position against the bias of said spring, a trip member for breaking said toggle means to permit the opening movement of said switch member by said spring, said extension engaging said trip member to return said trip member to its normal position as said switch member moves to its open circuit position.

3. A multipole switch comprising a plurality of stationary contacts, a plurality of movable contacts, a switch member formed of insulating material, means mounting said movable contacts on said switch member, pivot means pivotally mounting said switch member for movement between open and closed circuit positions, said switch member being provided with an upturned extension adjacent said pivot means, a spring normally biasing said switch member to said open circuit position, toggle means for holding said switch member in said closed position, a trip member for said toggle means, pivot means 25 mounting said trip member adjacent said extension, a spring biasing said trip member from a normal position to release said toggle means, a thermal device for restraining said trip member in a normal position against movement by its 30 associated spring, said thermal device being responsive to overload current and operable thereby to free said trip member to open said switch, said extension during the opening of said switch engaging said trip member to return the same 35 to its normal position.

4. In combination, a multi-pole switch comprising a switch member formed of insulating material, pivot means pivotally mounting said switch member for movement between open and closed circuit positions, an operating handle movable between on and off positions, a normally rigid operating connection between said handle and said switch member, a trip member provided with an extension normally maintained in a normal 45 position and out of engagement with said operating connection, a spring biasing said trip member and said extension into engagement with said operating connection to cause operation of said switch member to said open circuit position irrespective of the position of said handle, a thermal overload device for maintaining said trip member in said normal position comprising a restraining member provided with two arms, gear wheels normally maintaining said arms in fixed 50 position, solder films for said wheels normally maintaining them stationary and responsive to overload current to free said gears for rotation, the resulting movement of said restraining member into engagement with said trip member effecting the opening of said switch, and means forming a connection between said switch member and said trip member effective during the opening of said switch to reset said thermal device.

5. A thermal switch comprising a switch member operable between open and closed circuit positions, pivot means for said switch member, an extension provided on said switch member adjacent said pivot means, a bifurcated trip member having its respective arms located on opposite sides of said extension, means biasing said switch member to said open circuit position, toggle means for holding said switch member in said closed circuit position, one arm of said trip member being operable into engagement with

said toggle means to cause the operation of said switch member to its open circuit position, a pair of solder film overload devices, a restraining member provided with a pair of arms respectively engaging said solder film devices, said restraining member being provided with a slot into which said other arm of said trip member extends, biasing means for biasing said trip member to trip said latching means, said restraining member and said arms preventing movement of said trip member except during the occurrence of an overload on one or the other of said solder film devices.

6. A thermal switch comprising a base formed of insulating material, a switch member, means pivotally mounting said switch member on one side of said base for movement between open and closed circuit positions, biasing means for biasing said switch member to said open circuit position, a resetting extension provided on said switch member adjacent said pivot means, a bifurcated trip member having its respective arms located on opposite sides of said extension, toggle means for holding said switch member in said closed circuit position, means biasing said trip member for movement of one arm into engagement with said toggle means to cause the operation of said switch member to its open circuit position, the second arm of said trip member extending through said base, thermal overload responsive means supported from the side of said base opposite said switch member for holding said trip member in a normal position, said resetting extension rigidly engaging said second arm of said trip member to reset said trip member after the release of said trip member by said thermal overload means upon movement of the switch member to said open circuit position.

7. A switch comprising a base formed of insulating material, a contact supporting switch member, means mounting said switch member on one side of said base for movement between open and closed circuit position, an opening spring normally biasing said switch member to said open circuit position, a switch operating handle movable between on and off positions, a double link toggle connected between said handle and said switch member for holding said switch member in said closed position against the bias of said opening spring, a resetting extension secured to said switch member adjacent said pivot means, a bifurcated trip member pivoted at one end adjacent said handle, one arm of said trip member normally occupying a position on one side of said resetting extension and adjacent to the knee of said toggle, the other arm of said trip member extending through said base to the opposite side thereof, a tripping spring connected to said second arm of said trip member for biasing said trip member for movement from a normal position to break said toggle, 50 a pair of solder-film overload devices located on opposite sides of said second arm of said trip member, and latching means mounted on said opposite side of said base and normally engaging said second arm of said trip member and said overload devices for holding said trip member in said normal position, said resetting extension rigidly engaging said second arm as said switch member moves to its open circuit position to return said trip member and said latching means to their normal positions against the bias of said tripping spring.

8. A switch comprising a switch arm, means pivotally mounting said switch arm at one end, a resetting extension on said switch arm adjacent

said pivot extending substantially at right angles with respect to said switch arm, switch contacts carried on the other end of said arm, means biasing said switch arm from a closed to an open 5 circuit position, an operating handle, a releasable operating connection between said handle and said switch arm for maintaining said switch arm in said closed position, a trip member biased for movement to release said connection, an overload responsive device normally holding said trip member against its bias, said trip member having a portion arranged to be engaged by said resetting extension upon movement of said switch member to its open circuit position after release 10 of said trip member by said overload device whereby said trip member is returned to a position to be held by said load responsive device.

9. A switch comprising a switch arm made of insulating material, means pivotally mounting 20 said switch arm at one end, a resetting extension on said switch arm adjacent said pivot extend-

ing substantially at right angles with respect to said switch arm, means biasing said switch arm for movement from a closed to an open circuit position, an operating handle, means pivotally mounting said handle, toggle means forming an operating connection between said handle and said switch arm and operable to hold said switch arm in said closed position against its bias, said toggle being normally overset to hold said switch arm in said closed position, a trip member biased for movement against said toggle to thereby release said operating connection, thermal overload responsive means for holding said trip member against its bias, said trip member having a portion arranged to be engaged by said resetting extension when said switch arm moves to said open circuit position whereby said trip member is returned to its original position for engagement by said thermal overload means. 10 15
